Patented May 5, 1903.

UNITED STATES PATENT OFFICE.

ARTHUR B. RISLEY, OF HOBOKEN, NEW JERSEY.

DESIGN FOR A MATCH-SCRAPER.

SPECIFICATION forming part of Design No. 36,309, dated May 5, 1903.

Application filed April 8, 1903. Serial No. 151,683. Term of patent 7 years.

To all whom it may concern:

Be it known that I, ARTHUR B. RISLEY, a citizen of the United States, residing at Hoboken, in the county of Hudson and State of New Jersey, have invented and produced a new, original, and ornamental Design for a Match-Scraper, of which the following is a specification, reference being had to the accompanying drawing, forming a part thereof, in which is shown a perspective view of a match-scraper embodying the features of my design.

The design consists in a background which represents a barn, a match-receptacle which is in the form of a feed-box and represented as supported in close relation to the barn, and

in the representation of a burro or donkey in relief waiting for the feed supposed to be contained in the feed-box.

Having thus described my invention, I claim as new and desire to secure by Letters Patent—

The design for a match-scraper herein described and shown.

In testimony whereof I have signed my name to this specification in the presence of two subscribing witnesses.

ARTHUR B. RISLEY.
